TURTLE POOL

George J. Gould, 791 Meachem Ave., Elmont, N.Y.

Filed July 21, 1965, Ser. No. 86,233

Term of patent 3½ years

(Cl. D31—3)

FIG. 1 is a top perspective view of a turtle pool, showing my design;

FIG. 2 is a top plan view;

FIG. 3 is a sectional view taken on the line 3-3 of FIG. 2;

FIG. 4 is a side elevational view; and

FIG. 5 is an end elevational view.

I claim:

The ornamental design for a turtle pool, as shown.
